UNITED STATES PATENT OFFICE.

JOE HORN, OF KELVIN, ARIZONA.

RUBBER-SET RIFFLE.

1,351,250.

Specification of Letters Patent. Patented Aug. 31, 1920.

Application filed June 24, 1919. Serial No. 306,438.

To all whom it may concern:

Be it known that I, JOE HORN, a citizen of the United States, residing at Kelvin, in the county of Pinal and State of Arizona, 5 have invented new and useful Improvements in Rubber-Set Riffles, of which the following is a specification.

My invention relates to ore concentrating tables and my object is to make rubber set 10 riffles, and my invention consists of the novel features herein shown, described and claimed.

Figure 1 is a perspective of a riffle board for an ore concentrating table and provided with rubber riffles in accordance with the 15 principles of my invention.

Fig. 2 is a cross section on the line 2—2 of Fig. 1.

Fig. 3 is an enlarged fragmentary cross sectional detail on a plane parallel with 20 Fig. 2.

Fig. 4 is a fragmentary perspective detail.

In applying my rubber set riffles to a riffle board 1 I place a layer of tar paper 2 upon the upper face of the board 1. I cut strips 25 3 of board about an inch wide and three-eighths of an inch thick and place straight strips 4 of linoleum upon the strips 3 and cut the riffle plates 5 from thin sheet metal. Then I start from the side wall 6 which ex- 30 tends upwardly from one side of the board 1 and lay down two of the strips 3 with the strips 4 and drive nails 7 suitable distances apart to hold the strips in place and make a double width space 8. Then I apply a 35 coating of adhesive material, such as rubber cement, to the exposed edges of the strips 3 and 4 which have just been secured in place and place the riffle plate 5 against the adhesive material, and apply adhesive material 40 to the third strips 3 and 4 and place the strips against the riffle plate 5 and apply the nails and so on until the desired number of riffles have been applied to the board.

The nails 7 are driven so as to press the 45 strips 3 and 4 firmly against the riffle plates 5 and so that when the adhesive material sets and dries water tight joints are formed to prevent the water from soaking through the facing of the board around the riffle plates. 50 By using the wooden strips 3, I am able to use thinner linoleum strips 4.

The layer of tar paper 2 and the coatings of adhesive material against the edges of the strips 3 completely surround the strips 55 with water proof material so that they will not soak water and expand.

The rubber set riffles thus constructed are cheaply and easily made and quickly applied and produce a good concentrating table.

The board 1 forms the deck of the concentrating table.

Various changes may be made without departing from the spirit of my invention as claimed.

I claim:

1. In a concentrating table or the like, a wooden deck, a layer of tar paper upon the deck, wooden strips upon the layer of tar paper, linoleum strips upon the wooden strips, and sheet metal riffle plates upon the tar paper between the wooden strips and between the linoleum strips, and water proofing cement coating for the bottom and side edges of the wooden and linoleum strips. 75

2. In a concentrating table or the like, a wooden deck, a layer of tar paper upon the deck, wooden strips upon the layer of tar paper, linoleum strips upon the wooden strips, sheet metal riffle plates upon the tar paper between the wooden strips and between the linoleum strips, a water proofing cement coating for the bottom and sides of the wooden and linoleum strips and means for holding the strips to the deck and the metallic riffles between the strips. 80

3. In a concentrating table or the like, a wooden deck, a layer of tar paper upon the deck, wooden strips upon the layer of tar paper, linoleum strips upon the wooden strips, sheet metal riffle plates upon the tar paper between the wooden strips and between the linoleum strips, and water proof cement on the side edges of said wooden strips and said linoleum strips securing said 90 metallic riffles thereto. 95

4. In a concentrating table, a wooden deck, a layer of tar paper upon the deck, wooden strips upon the layer of tar paper, linoleum strips upon the wooden strips, sheet metal riffle plates upon the tar paper between the wooden strips and between the linoleum strips, and nails driven through said linoleum strips, wooden strips and tar paper into said wooden deck to hold the parts 100 firmly together. 105

In testimony whereof I have signed my name to this specification.

JOE HORN.
